UNITED STATES PATENT OFFICE

WILLIAM JOHN CRONAN, OF WETHERSFIELD, CONNECTICUT

DESIGN FOR A VEHICLE DIRECTION SIGNALING LIGHT

Application filed February 9, 1932. Serial No. 42,787. Term of patent 14 years.

To all whom it may concern:

Be it known that I, WILLIAM JOHN CRONAN, a citizen of the United States, residing at Wethersfield, in the county of Hartford and State of Connecticut, have invented a new, original, and ornamental Design for a Vehicle Direction Signaling Light, of which the following is a specification, reference being had to the accompanying drawings, forming part thereof.

In the drawings

Figure 1 is a top view of my vehicle direction signaling light; and

Figure 2 is a front view thereof.

I claim:

The ornamental design for a vehicle direction signaling light, as shown.

In witness whereof, I hereunto subscribe my name this 5th day of February, 1932.

WILLIAM J. CRONAN.
